UNITED STATES PATENT OFFICE.

BRUNO JESCHKE, OF OAKLAND, CALIFORNIA.

ARCH SUPPORT.

Application filed September 26, 1920. Serial No. 411,632.

To all whom it may concern:

Be it known that I, BRUNO JESCHKE, a citizen of the United States, residing at the city of Oakland, in the county of Alameda 5 and State of California, have invented certain new and useful Improvements in Arch Supports, of which the following is a specification.

This invention relates to improvements in 10 orthopedic appliances and more particularly to a support for the arch of the foot.

My device is intended not only to support fallen arches but also to protect high arches by preventing them from breaking down. 15 I aim to provide a device, one side of which fits the shoe and the other side of which fits the sole of the foot.

My device at the center portion is hard 20 and rigid while the edges and especially the portion under the heel and ball of the foot are more or less flexible, which construction enables the device to accommodate itself to the motions of the foot when the user is walking.

With these and other objects in view, my 25 invention consists in the novel features and manner of construction herein described and more particularly pointed out in the appended claims.

Reference being had to the accompanying 30 drawings forming a part of this specification:

Figure 1 is a view in perspective of my improved appliance.

Figure 2 is the bottom plan view of the 35 same.

Figure 3 is a view in cross section, substantially on the line 3—3 Figure 1.

Figure 4 is a view in section through the 40 device showing the mould used in forming it under pressure.

Referring to corresponding parts in the several views by the same numerals of reference: 1 denotes in general the improved appliance, which is formed with the rounded portion 2 which fits within the heel of the shoe and under the heel of the foot. Extending forwardly from this point on one side of the supporter, is the upwardly convex portion as shown at 3, this portion resting under inside of the arch.

The center part of the appliance opposite this upwardly convex portion is thickened as shown at 4 and is formed of two layers 55 of leather. These layers are fastened together by means of a large number of

closely spaced nails as shown at 5. The nails have a head 6 and are driven from the under side of the appliance and clinched on the inside. By driving the nails closely as here 60 illustrated the fibre of the leather is compressed between them and the supporter at this portion is made very rigid and perfectly retains its shape in use. These nails, in effect, act in the same manner as the strut 65 rods of a truss and so prevent deformation of the device by the weight of the foot.

From this thickened portion, the supporter tapers to a thin edge at its forward point 7, and the whole inner surface is 70 covered with a smooth layer of leather indicated by 8.

In forming this appliance I first cut the leather to the proper shape and then soak 75 the same in water. I then scarf the edges as well as the edges of the small piece 9. These two pieces are then placed together and temporarily held with two nails while placed between the two sections of a mould. The mould is placed in a press where it is 80 subjected to a very great pressure so as to thoroughly compress the fibre of the leather. The shape of the mould surfaces are that of the finished supporter which is allowed to dry in the mould. After the same has 85 dried and been removed from the forms they retain their shape while the nails are being driven into the two parts. After the two pieces are thoroughly attached by the closely spaced nails, the upper and lower 90 surfaces are smoothly finished on a sanding machine and then the lining 8 is cemented in place.

The mould sections above referred to comprise a base section 10 which is curved 95 at 11 to conform to the bottom of the supporter, an intermediate section 12 which is curved at 13 to give the required shape to the upper surface of the supporter. One of these sections has spring clips 15 which engage the other section and hold them together while the device is drying.

The section 16 is common to all moulds and is only used to provide a flat face while the pressure is being placed on the parts 105 10 and 12.

In use the appliance is inserted in the shoe in the usual manner with the curved rear portion 2 in the heel and the forward edge 7 on the sole of the shoe. Then the 110 rigid hard center portion 4 forms a bridge between the heel and sole and this rigidity

prevents it from being crushed down. Under these conditions the upper surface forms a most efficient support for the arch of the foot. At the same time there is some resiliency to this portion of device while the front and rear portions are quite flexible. In this manner the appliance is most effective in supporting the arch and yet permitting the sole of the foot to act in a natural manner in walking.

Having thus described my invention, I claim as new and wish to cover by Letters Patent;

1. An arch supporter comprising a body of leather curved on its opposite faces to conform to the shape of a foot and shoe, said body having a plurality of closely spaced nails driven through the center por-

tion thereof to hold the same substantially rigid, and a continuous tapered and flexible edge on said body around said substantially rigid center portion.

2. An arch supporter comprised of layers of leather curved on the opposite faces to fit a foot and shoe, and having a thickened center portion terminating in a continuous tapered and flexible edge; and a plurality of rigid fastening means passed through said thickened center portion to hold the same substantially rigid, the entire arch supporter being substantially resilient and capable of sustaining its shape.

In testimony whereof I affix my signature.

BRUNO JESCHKE.
